Design No. 444

SAMUEL EBERLY'S
Design for a Stove.

DES 477

Patente ab 3. Augt. 1852.

G. C. Humphries, Del.

June

Samuel Oberly of Mechanicsburg Penna;
Letters Patent No 477. Dated Aug 3rd 1852

The schedule referred to in these Letters Patent and making part of the same.

To all whom it may concern:

Be it known that I Samuel Oberly of Mechanicsburgh in the County of Cumberland and State of Pennsylvania have invented or produced a new and original Design for a Book Stove, and I do hereby declare that the following is a full and exact description of the same reference being had to the annexed drawing which represents an elevation of one of the sides of the Stove.

A is an ornament in bas relief in the centre of a panel D of the oven door resembling the Antient Lyre.

B is a foliated raised ornament arranged in the centre of the small panel E of the fire chamber surrounded by plain parallel raised mouldings or borders.

C is another foliated raised ornament of a novel and graceful form arranged in the centre of the small panel which relieves or enriches the blank space below that containing the ornament B.

The blank space above the oven door is relieved by the words
"UNION. AIR TIGHT"

Having thus described my design for a Book Stove, what I claim as new and desire to secure by Letters Patent is the combination of the ornaments A B C

2

Des. 477

with the panels D. E. F. raised on the surface of the side plate of the stove.

In testimony whereof I have hereunto signed my name before two
subscribing witnesses.
